No. 36,846.

Patented March 8, 1904.

UNITED STATES PATENT OFFICE.

CHARLES A. HARTMAN, OF DENVER, COLORADO.

DESIGN FOR A PICTURE-FRAME MAT.

SPECIFICATION forming part of Design No. 36,846, dated March 8, 1904.

Application filed December 26, 1903. Serial No. 186,712. Term of patent 14 years.

To all whom it may concern:

Be it known that I, CHARLES A. HARTMAN, a citizen of the United States of America, residing in the city and county of Denver and State of Colorado, have invented a new, original, and ornamental Design for a Picture-Frame Mat, reference being had to the accompanying drawing, which forms a part of this specification.

This invention relates to a new, original,

and ornamental design for a picture-frame mat, and the accompanying drawing is a plan view of the mat.

What I claim is—

The ornamental design for a picture-frame mat as shown in the drawing.

CHARLES A. HARTMAN.
